UNITED STATES PATENT OFFICE

HENRY BIANCO, OF BALTIMORE, MARYLAND, ASSIGNOR TO CAMPBELL METAL WINDOW CORPORATION, OF BALTIMORE, MARYLAND, A CORPORATION OF MARYLAND

SEALING MECHANISM FOR WINDOWS

Application filed August 2, 1930. Serial No. 472,630.

In Campbell Patent No. 1,673,393, issued June 12, 1923, is described a sealing mechanism for use with windows having openings through the inner walls of the jambs and having separate enlarged chambers back of such openings with sashes having plates adapted to extend through such openings. In that patent the sealing mechanism is arranged to provide a seal inside the jamb between the sash plate and a parting strip or baffle, which forms a part of the inner jamb wall, and at the same time it is so arranged that the sash is free to move in both horizontal directions without being held by spring pressure. Also all the sealing mechanism is anchored within the jamb and very little, if any, is visible.

In the Campbell application, Serial No. 383,190, filed August 3, 1929, for sealing mechanism for metal windows, is described a method of maintaining the sash plates under tension so that they are drawn towards the baffle or parting strip, avoiding a tendency of the sash to rattle.

According to my present invention, which relates to sealing mechanism of the general type and character described above, I provide a wide strip of metal weather stripping which completely covers the parting strip or baffle upon its inner wall, being anchored thereon, and which has projecting flanges which combine with proper sealing strips upon the sash plates in order to give tension so that the sash plates may be drawn towards the parting strip to avoid rattle. This construction also avoids complexity in assemblage as it permits the large strip simply to be slipped over the baffle on its inner face and there positioned by the same screws which anchor the baffle. The advantages in simplicity of structure and in assembly are manifest to those skilled in the art.

It is to be understood that the illustrative example set forth in the accompanying drawings can be easily modified to include the feature of the felt pocket upon the sash plate weather stripping as shown in my copending application for absorbent weather stripping for windows, Serial No. 453,920, filed May 20, 1930, and that it may also be modified to in-

clude the same type of dissimilar metal sheathing placed upon the sash plate as illustrated in said absorbent weather stripping application.

Furthermore, in metal windows, such as 55 aluminum, a dissimilar metal weather stripping jacket, formed for instance of zinc, over the baffle will prevent binding between the baffle edge and the sash plate.

In the accompanying drawings, Fig. 1 represents a cross section of a part of a metal window incorporating my invention; Fig. 2 is a fragmentary side elevation of the inner jamb wall, showing the weather stripping jacketed over the baffle, and Fig. 3 represents 65 a perspective view of a weather stripping jacket adapted to be placed over the baffle, with the proper flanges to enter the sash plate openings.

In the figures, a wide metal weather strip designated as 10 is jacketed over the parting strip or baffle 12, in such manner that two projecting flanges 14 and 16 enter the enlarged chambers 18 and 20 preferably at an angle of slightly less than 90°, although this angle of entrance may be varied greatly in practice. Upper sash plate 22, and lower sash plate 24 respectively enter the enlarged openings 18 and 20 through the spaces between the baffle 12 and chain pocket 26, and 75 cover 28.

As illustrated spring members 30 are hooked around the edges of the respective sash plates and in such manner as to move with the sash plates, and have a forwardly 85 projecting arm designated as 31 which is adapted to maintain a spring tension and sliding contact with the inner sides of flanges 14 and 16 of the baffle jacket weather stripping 10. Thus a portion of the flanges projects between a part of the spring members 30 and the sash plates. Although not shown in the drawings, it is manifest that spring members 30, if desired, could be provided with the felt pockets as an additional guard 90 against the entrance of wind and rain, as shown in my application, Serial No. 453,920 aforesaid.

As indicated by Figures 2 and 3, the baffle weather stripping jacket 10 is preferably 100

notched at 32 to allow the positioning of rubbing block 34, although this notching is not strictly necessary, as the rubbing block could be mounted if desired over the baffle weather stripping jacket.

5 It is apparent that the spring tension between flanges 14 and 16 and spring members 30 should, in order to gain the full advantages described, be light enough to gently draw the sash towards the baffle to prevent rattling, and yet not be of such force so that serious binding between the sealing members and jacket flanges will take place. Ordinarily speaking the baffle weather stripping jacket will be of such construction that its flange members will not have a great deal of springiness, but it is obvious that this may be modified at will to include some resiliency.

10 20 It will be seen that where the metals employed in the construction of the window tend to bind, such as aluminum, that by interposing between plates 22 and 24 and the edges of baffle 12, a jacket 10 of a dissimilar metal, such as zinc, that binding due to similarity of metals, such as formerly took place between the baffle and sash plate will be eradicated.

25 30 As shown by Figures 2 and 3, the baffle weather stripping jacket 10 is attached to the baffle by means of screws or bolts through the holes 36, and these same screws or bolts, if desired, may be the assemblage units for attaching the baffle to the partition strip in the customary manner.

35 40 From the foregoing description it will be seen that my invention consists, in this type of window, in the provision of a weather stripping jacket encompassing the inner wall of the baffle and projecting into the inner chambers in such fashion that where dissimilar metals are used that binding effects are avoided, and so that rattling is eradicated by slight tension placed upon the sash plates, drawing them towards the baffle, and also in the provision of a weather stripping unit extending substantially the entire length of the baffle in preferably integral fashion, having flanges at either side of the baffle to be used in conjunction with the usual spring members attached to the sash plates. The illustrative example set forth is an embodiment of my invention in a simple form but may be modified in many ways without departing from the spirit of my invention.

50 55 What I claim is:

1. In a window of the type having jamb openings through the inner walls of the jambs, a baffle forming part of the main jamb wall between such openings, sashes having members adapted to extend through such openings and resilient sealing members upon said sash members, a plate mounted upon the face of the baffle provided with flanges projecting into said openings between the

sash members and the baffle edge and contacting with said resilient sealing members, said flanges extending between the sash members and the sealing members.

2. In a window of the type having jamb 70 openings through the inner walls of the jambs, a baffle forming part of the main jamb wall between such openings, sashes having members adapted to extend through such openings, resilient sealing members upon said sash members and a rubbing block mounted upon said baffle, an integral sheet of metallic weather stripping running upwardly and downwardly the face of said baffle, said sheet having its edges bent to project 75 80 into said openings and being notched in its center for said rubbing block, said bent edges being adapted to contact with said sealing members under tension and extend between the sealing members and said sash members, whereby the sash plates are drawn 85 towards the baffle edges.

3. In a window of the type having jamb 90 openings through the inner walls of the jambs, a baffle forming part of the main jamb wall between such openings, sashes having members adapted to extend through such openings and resilient sealing members upon said sash members, a weather stripping jacket covering the face of the baffle but 95 notched to avoid any fixed members thereon and having edges bent into said openings at an angle of less than 90°, said edges adapted for contact upon their inner sides with said sealing members under tension, whereby said 100 sash members are under a gentle pull towards the edges of said baffle.

4. In a window of the type having jamb 105 openings through the inner walls of the jambs, a baffle forming part of the inner jamb wall between such openings, sashes having members adapted to extend through such openings and resilient sealing members upon said sash members, fixed weather stripping mounted upon the face of the baffles, and adjacent thereto, said weather stripping being provided with flanges projecting into said 110 openings between the sash members and the baffle edge, said weather stripping being formed of different metal than said baffle and sash members, whereby all binding between the sash member and baffle due to similarity 115 of metals is avoided.

5. In a window of the type having jamb 120 openings through the inner walls of the jambs, a baffle forming part of the inner jamb wall between such openings, separate enlarged chambers back of such openings, sashes having members adapted to extend through such openings and resilient sealing members upon said sash members, a metal strip encompassing the face of said baffle and attached thereto having its edges bent to project between the edges of the baffle and the sash members and adapted to serve as a 125 130

contact slide for the sealing members upon said sash members.

6. A structure as defined in claim 5 wherein the metal strip is formed of different metal
5 than the baffle and the sash members, whereby binding due to similarity of metals is eradicated.

7. In a window of the type having jambs, openings through the inner walls of the
10 jambs, a baffle forming part of the main jamb wall between such openings, sashes having members adapted to extend through such openings and resilient sealing members upon
15 said sash members, a weather stripping jacket covering the face of the baffle but notched to avoid any fixed members thereon and having edges bent into said openings, said sealing members contacting with the inner sides of said edges whereby the sash members
20 may be tensioned towards the baffle and the seal between the jacket edges and the sealing members tightened as the sash is moved from the baffle.
